CLAIM

The ornamental design for a trunk, as shown and described.

DESCRIPTION

FIG. 1 is a perspective view of a trunk showing our new design in an embodiment;

FIG. 2 is a front view thereof;

FIG. 3 is a rear view thereof;

FIG. 4 is a left side view thereof;

FIG. 5 is a top view thereof;

FIG. 6 is a bottom view thereof;

FIG. 7 is a perspective view thereof with a handle extended;

FIG. 8 is a right side view with the handle shown in a closed configuration;

FIG. 9 is a perspective view in an open configuration;

FIG. 10 is a perspective view thereof in a second embodiment;

FIG. 11 is a front view thereof;

FIG. 12 is a rear view thereof;

FIG. 13 is a left side view thereof;

FIG. 14 is a top view thereof;

FIG. 15 is a bottom view thereof;

FIG. 16 is a perspective view thereof with the handle extended;

FIG. 17 is a right side with the handle shown in a closed configuration; and,

FIG. 18 is a perspective view in the open configuration.

The broken lines shown in the drawings illustrate portions of the trunk and form no part of the claimed design.
